CIRCUIT BREAKER LEVER

Charles H. Davis, Jr., deceased, late of Anderson, Ind., by John T. Fitzsimmons, Anderson, Ind., administrator, assignor, by mesne assignments, to General Motors Corporation, Detroit, Mich., a corporation of Delaware

Application April 21, 1932, Serial No. 606,663

10 Claims. (Cl. 200—30)

This invention relates to ignition timers for internal combustion engines.

One of its objects is to provide an ignition timer which will operate satisfactorily at very high speed.

This and other objects of the invention are accomplished by providing a circuit breaker lever of extreme rigid and light weight construction. In a Reissue Patent Number 19,083 issued February 13, 1934 there is provided a very light weight, rigid lever by folding over a thin metal sheet so as to form a double thickness of the material. Each thickness is provided with means for attaching the lever to a hub by which the lever is journaled upon a support, with means for attaching a rubbing block and with means for attaching a contact. In the present form of the invention a sheet of the metal is not doubled over but forms the lever of separate pieces in a manner which will be apparent from the following description.

Further objects and advantages of the present invention will be apparent from the following description, reference being had to the accompanying drawing, wherein a preferred embodiment of one form of the present invention is clearly shown.

In the drawing:

Fig. 1 is a plan view of an ignition timer having a circuit breaker lever embodying the present invention.

Fig. 2 is a side view of the circuit breaker lever drawn twice the size as shown in Fig. 1.

Fig. 3 is a view in the direction of the arrow 3 of Fig. 2.

Fig. 4 is a sectional view on the line 4—4 of Fig. 2.

Fig. 5 is a view of the spring looking in the direction of the arrow 5 of Fig. 3.

Fig. 6 is a sectional view on the line 6—6 of Fig. 3.

Fig. 7 is a view of the rubbing block looking in the direction of the arrow 7 of Fig. 3.

Fig. 8 is a view looking in the direction of the arrow 8 of Fig. 7.

Referring to Fig. 1, the ignition timer includes a housing 20 supporting a plate 21 carrying a pivot post 22 upon which are pivoted a stationary contact bracket 23 and the circuit breaker lever 24 embodying the present invention. The lever 24 comprises two sheet metal parts 30 and 31, which are alike, except that one is punched right hand and the other left hand, so as to provide the members 30 and 31 respectively with flanges 32 and 33 surrounding

holes which are brought into alignment and through which a nonconducting bushing 34 may extend.

The parts 30 and 31 provide oppositely extending ears 36 and 37, respectively, which are provided with holes for receiving rivets 38 and 39, respectively, which also pass through holes 40 and 41, respectively, in a rubbing block 42 of non-conducting material and through holes 44 and 45 respectively provided by a leaf spring 10 conductor 46. Thus the rivets 38 and 39 secure to the ears 36 and 37 the rubbing block 42 and the spring 46. The rubbing block 42 is provided with a slit 43 to enable the rubbing block 42 to straddle the two pieces 30 and 31, and the spring 15 46 is also provided with a slit 47 to permit the spring 46 to straddle the pieces 30 and 31. Thus the rubbing block 42 and the spring 46, being attached by the rivets 38 and 39, secure the lever parts 30 and 31 together at a point intermediate the ends of the lever.

The lever parts 30 and 31 are provided with oppositely extending ears 50 and 51 respectively which together provide a plane surface for receiving a contact 52 attached to the ears preferably by welding.

The circuit breaker though light in weight is extremely rigid due to the fact that the two thin sheets of metal 30 and 31 are tied together at their ends and at an intermediate point. The contact 52 ties the two parts together at the free end of the lever where the contact is joined to the ears 50 and 51. The other or pivoted end of the lever parts 30 and 31 are joined together by the bushing 34 which is fixed in position by deforming the flanges 32 and 33 in the grooves 32a and 33a, provided by the bushing 34. As stated before, the rubbing block 42 ties the lever parts 30 and 31 together at an intermediate portion through the connection between the 40 rubbing block 42 and the ears 36 and 37.

Since the circuit breaker lever 24 can be made very rigid by this construction it is apparent that very thin metal can be employed for its construction, thereby reducing the polar inertia of the circuit breaker lever to a very low value. In this way the circuit breaker will operate at extremely high speed without "chattering" due to the rebounding of the contact 52 from a stationary contact 60 carried by the stationary contact bracket 23.

The spring 46 is attached to an insulated terminal 70 carried by the housing 20 and serves to conduct current from said terminal to the contact 52 as well as to urge the rubbing block 42

toward an operating cam 71 and to urge the contact 52 against the contact 60 when the cam 71 releases the rubbing block 42.

While the form of embodiment of the present invention as herein disclosed, constitutes a preferred form, it is to be understood that other forms might be adopted, all coming within the scope of the claims which follow.

What is claimed is as follows.

1. A circuit breaker lever comprising two sheet metal stampings so shaped that, when the stampings are juxtaposed, two aligned, oppositely extending, annular flanges are provided; a bushing extending through both flanges; an electrical contact attached to ears projecting from the stampings; and a rubbing block attached to the stampings.

2. A circuit breaker lever comprising two sheet metal stampings so shaped that, when the stampings are juxtaposed, two oppositely extending flanges are provided which lie in the same plane parallel to the axis of the lever; an electrical contact attached to both flanges; a rubbing block attached to flanges projecting from the stampings; and a bearing bushing extending through an opening provided by the stampings.

3. A circuit breaker lever comprising two sheet metal stampings so shaped that, when the stampings are juxtaposed, there are provided two aligned, oppositely extending, annular flanges, and two plane flanges extending oppositely and located in the same plane parallel to the axis of the lever; a bushing extending through both annular flanges; a rubbing block attached to both plane flanges; and an electrical contact attached to parts projecting from both stampings.

4. A circuit breaker lever comprising two sheet metal stampings so shaped that, when the stampings are juxtaposed, there are provided two pairs of oppositely extending, plane flanges, each pair lying in a plane parallel to the axis of the lever; a rubbing block attached to one pair of plane flanges; an electrical contact attached to another pair of plane flanges; and a bearing bushing attached to tubular means projecting from both stampings.

5. A circuit breaker lever comprising two sheet metal stampings so shaped that, when the stampings are juxtaposed there are provided two pairs of oppositely extending, plane flanges, each pair lying in a plane parallel to the axis of the lever and two aligned, oppositely extending, annular flanges; a rubbing block attached to one pair of plane flanges; an electrical contact attached to another pair of plane flanges; and a bearing bushing extending into the annular flanges.

6. A circuit breaker lever comprising two sheet metal stampings so shaped that, when the stampings are juxtaposed, two oppositely extending flanges are provided which lie in the same plane parallel to the axis of the lever; a rubbing block and a leaf spring conductor attached to both flanges; an electrical contact attached to parts extending from the stampings, and a bearing bushing attached to tubular means projecting from the stampings.

7. A circuit breaker lever comprising two sheet metal stampings so shaped that, when the stampings are juxtaposed, there are provided two pairs of oppositely extending, plane flanges, each pair lying in a plane parallel to the axis of the lever; a rubbing block and a leaf spring conductor attached to one pair of plane flanges; an electrical contact attached to another pair of plane flanges; and a bearing bushing attached to both stampings.

8. A circuit breaker lever comprising, in combination; a plurality of juxtaposed flat plates; a contact secured to one or more of the plates; a rubbing block attached to one or more of the plates; a pivot member passing through all of the plates; and means including portions of the plates for attaching the pivot member to the plates whereby the pivot member ties the plates together.

9. A circuit breaker lever comprising, in combination; a plurality of superposed plates; a contact and a rubbing block attached to the plates; a pivot member passing through the plates; and annular flanges integral with the plates and extending laterally therefrom in opposite directions and tightly fitting around the pivot member whereby said pivot member holds the plates together.

10. A circuit breaker lever comprising, in combination; a plurality of flat plates; a pivot member and a contact carried by the plates; a leaf spring and an L-shaped rubbing block both extending laterally beyond the outer sides of the plates, one leg of said rubbing block providing a cam-engaging surface at one end thereof, and the other leg of the rubbing block being notched to receive the plates; flanges extending from the plates and at substantially right angles to the plane of the plates; and means for securing the notched leg and one end of the leaf spring to the flanges of the plates to hold all of the plates together.
